US00D962056S

(12) **United States Design Patent** (10) **Patent No.:** **US D962,056 S**
Le et al. (45) **Date of Patent:** **** Aug. 30, 2022**

(54) **ELECTRONIC DEVICE HOUSING**

(71) Applicant: **Google LLC**, Mountain View, CA (US)

(72) Inventors: **Minh-Nhat Le**, San Jose, CA (US);
James Dwight McLurkin, Seattle, WA (US);
Kai Yick, Daly City, CA (US);
William Rutledge, San Francisco, CA (US)

(73) Assignee: **GOOGLE LLC**, Mountain View, CA (US)

(**) Term: **15 Years**

(21) Appl. No.: **29/738,380**

(22) Filed: **Jun. 17, 2020**

Related U.S. Application Data

(63) Continuation of application No. 29/644,114, filed on Apr. 13, 2018, now Pat. No. Des. 890,720.

CLAIM

The ornamental design for an electronic device housing, as shown and described.

DESCRIPTION

FIG. 1 is a top, left, front perspective view of an electronic device housing, showing our new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The material shown in FIGS. 1-7 is of uniform thickness.

(Continued)

The broken lines of even length shown in the drawings illustrate portions of the electronic device housing that form no part of the claimed design.
